UNITED STATES PATENT OFFICE.

ERNON V. OLIVER, OF PORTLAND, OREGON.

CONDENSER FOR STILLS.

Application filed March 5, 1925. Serial No. 13,283.

This invention relates to improvements in water stills and more particularly to a novel condenser for such a still.

One of the objects of the present invention is to provide a condenser so constructed that the cooling water will be supplied to the condenser at the most advantageous point to effect rapid and thorough condensation of the water vapors delivered from the generator with which the condenser is associated.

Another object of the invention is to provide a condenser so constructed that obnoxious volatile impurities contained in the water being distilled will be carried off so that the distilled water will be free from contamination.

Another object of the invention is to provide a condenser embodying means whereby air may be partially exhausted from the condensation chambers of the condenser to thereby not only remove obnoxious volatile impurities which may be contained in the water or water vapors but, at the same time, expedite and facilitate the vaporization of the water and the condensation of the vapors.

In the accompanying drawings:

Figure 1 is a vertical sectional view through a distilling apparatus constructed in accordance with the present invention.

Figure 2 is a horizontal sectional view taken substantially on the line 2—2 of Figure 1, looking in the direction indicated by the arrows.

The distilling apparatus embodying the invention comprises, generally speaking, a generator, indicated in general by the numeral 1, a receiver, indicated by the numeral 2, and a condenser indicated in general by the numeral 3, the apparatus further comprising an exhausting unit which is indicated in general by the numeral 4. The generator 1 and receiver 2 are of the construction illustrated and described in my co-pending application Serial Number 678,451, filed December 4, 1923, and, consequently, a brief description of these component parts of the apparatus will suffice. The generator 1 comprises a hollow body which, in the present illustrated embodiment of the invention, is of rectangular form, although it may assume the cylindrical form shown in my co-pending application, Serial Number 678,450, filed December 4, 1923, and comprises a surrounding wall or walls indicated

by the numeral 5 and other walls 6 which are spaced inwardly from the walls 5 and connected therewith by a bottom 7 forming a preheating chamber 8 into which water is introduced by a supply pipe 9 provided at its top with a funnel 10, the purpose of which will be presently explained. A bottom wall 11 is arranged within the bounds of the walls 6, and defines, in conjunction with the upper portions of said walls 6, a generating chamber 12, the walls 6 having openings 13 therein to provide for the passage of preheated water from the preheating chamber 8 to the generating chamber 12, whereby a constant shallow level of water is maintained upon the bottom 11 which is rapidly converted into steam, the apparatus being, of course, arranged with the open bottom of the generator above a source of heat, as, for example, a cooking range. A plate 14 is arranged within the generator 1 and rests upon the upper edges of the walls 6 and is formed with perforations 15 and 16 located respectively above and communicating with the pre-heating chamber 8 and generating chamber 12, so that the steam generated in these chambers, and especially in the chamber 12, may pass upwardly through the open top of the generator.

The receiver 2 comprises a hollow body 17 provided in its upper portion with a receiving pan 18 having a number of short nipples or spouts 19 extending upwardly from its surface and establishing communication between the spaces above and below the pan. A water outlet pipe 20' leads from the lowermost portion of the pan, the pan being inclined from all sides toward its said portion, and serves to carry off the distilled water. The body of the receiver is removably disposed upon the open top of the body of the generator and the condenser 3 is, in turn, removably supported upon the top of the receiver.

The condenser 3 comprises a hollow body defined by surrounding walls 20, and the said body is removably disposed at its lower end to rest upon the open top of the receiver 2 and is provided above its open bottom with a bottom plate indicated by the numeral 21, this plate being formed with a plurality of openings 22 which, in the present instance, are of rectangular form. Condensation chambers, indicated in general by the numeral 23, are fitted and secured in a fluid-tight manner at their lower ends in

the openings 22 or may be secured to the plate 21 in position to register at their said ends with the said openings, these ends of the chambers being open. The condensation chambers 23 are of rectangular section and of any desired dimensions and arranged in any desired manner over the area of the plate 21, and the said chambers are closed at their upper ends by caps 24 preferably 10 permanently united thereto. The space enclosed by the body 20 of condenser 3 above the bottom 21 and surrounding the condensation chambers 23, constitutes a cooling-fluid chamber indicated by the numeral 25, and water or other suitable fluid is introduced into this chamber in regulated quantities by a system of piping which will now be described. The numeral 26 indicates a trunk line made up of pipe sections and 15 suitable elbows uniting the same, which surrounds the lower portion of the condenser body 20 in a plane immediately above the bottom 21 thereof, and a water supply pipe 27, leading from any suitable source of supply, is placed in communication with the trunk at any suitable point and is provided with a manually adjustable cut-off valve 28 whereby the flow of water to the trunk may 20 be controlled. A number of branch pipes 29 are placed in communication with the trunk 26 and lead inwardly therefrom and through the walls of the condenser body 20 and at their inner ends, which ends are in 25 communication with the interior of the condenser body or, in other words, with the cooling-fluid chamber 25, are preferably flared as indicated by the numeral 30. Preferably, the arrangement is such that the discharge end of each of the delivery pipes 29 will be positioned between two adjacent condensation chambers 23, except that 30 where such pipes are led through the corners of the body 20 of the condenser, the discharge ends of such pipes may be presented directly toward the corner chambers, as best shown in Figure 2 of the drawings, these particular branch pipes being indicated by the numeral 29'. At this point, it will be evident that the condensation chambers 23 are in communication, at their lower ends, with the space above the receiver 2 so as to receive the steam or water vapors rising through the nozzles 19, and it will likewise be evident that the cooling water or 35 other cooling fluid is supplied to the cooling-fluid chamber 25 substantially at the lower ends of the said condensation chambers 23 and is caused to circulate about the chambers and cool the walls thereof to effect condensation of the steam or water vapors.

The numeral 31 indicates an overflow pipe which leads from the cooling-fluid chamber 25 near the top thereof and to any suitable point where the overflow is to be 40 delivered, a manually adjustable cut-off 45

valve 32 being arranged in this pipe so as to regulate the overflow in accordance with the delivery of water to the said chamber. The numeral 33 indicates another overflow pipe which leads from the chamber 25 and 50 extends downwardly with its lower end entering the funnel 10, a manually operable cut-off valve 34 being interposed in this pipe to control the passage of water therethrough. It will be understood at this 55 point, that by providing the pipe 33, water may be delivered from the chamber 25 into the funnel 10 and discharged from the funnel through the pipe to the chamber 8. The exhausting unit 4 comprises a closed 60 chamber 35 of dimensions and contour to seat in or upon the upper end of the body 20 of the condenser 3, and short pipes 36 extend upwardly from the caps 24 of the condensation chambers 23 and establish communication between the upper ends of the said chambers and the bottom portion of the exhausting chamber 35. The numeral 37 indicates a pipe which is placed in communication at one end with the chamber 35 and leads to any suitable exhaust pump for exhausting air from the said chamber, a cut-off valve 38 being interposed in the pipe 37 whereby the outflow of air through 65 the pipe may be controlled.

In the operation of the apparatus, water reaching the surface of the bottom plate 11 of the generator will be immediately converted into steam and the steam will rise through the openings 16 in the plate 14 and through the nipples 19 in the pen 18 of the receiver 2, and enter the condensing chambers 23, where it will be condensed and dripped from these chambers onto the pan and delivered through the pipe 20. Due to 70 the suction created in the exhausting chamber 35, the steam is caused to more thoroughly circulate in the condensing chambers 23 and heated air currents will likewise be drawn off from these chambers, so that the steam is more rapidly cooled and rapidly and effectually condensed than would otherwise be the case. Likewise, all obnoxious volatile impurities in the water will be 75 drawn off by way of the chamber 35 and exhaust pipe 37, thereby avoiding contamination of the distilled water.

It will be evident that while the condensation chambers 23 are herein illustrated and described as of rectangular form, they 80 may assume some other form if found desirable, without departing from the spirit of the invention as expressed in the claims.

Having thus described the invention, what I claim is:

1. In distilling apparatus, a condenser casing having a body wall and a bottom, the latter provided with openings, a plurality of upright condensation chambers arranged within the casing upon the bottom thereof 90

within said openings, the said chambers being closed at their tops and open at their bottoms to receive the vapors to be condensed, a trunk pipe, means for supplying a cooling fluid thereto, and a plurality of branch pipes leading from the trunk pipe and into the casing through the body wall near the bottom of the casing and having their discharge ends presented in proximity 10 to the lower portions of the condensation chambers.

2. In distilling apparatus, a condenser casing having a body wall and a bottom, the latter provided with openings, a plurality 15 of upright condensation chambers arranged within the casing upon the bottom thereof, the said chambers being closed at their tops and open at their bottoms to receive the vapors, the bottoms of the chambers occupying the said openings, a trunk pipe, means 20 for supplying a cooling fluid thereto, and a plurality of branch pipes leading from the trunk pipe and into the casing near the bottom thereof and having their discharge 25 ends presented in proximity to the lower portions of the condensation chambers, the said ends of the pipes being flared.

3. In distilling apparatus, a condenser

casing having a body wall and a bottom, a plurality of upright condensation chambers 30 arranged within the casing upon the bottom thereof, closed at their upper ends and opening at their lower ends through the said bottom to receive the vapors, means for supplying a cooling fluid to the casing, and an 35 exhausting chamber in communication with the upper ends of the said condensation chambers.

4. In distilling apparatus, a condenser casing having a body wall and a bottom, a 40 plurality of upright condensation chambers arranged within the casing upon the bottom thereof, closed at their upper ends and opening at their lower ends through the said bottom to receive the vapors, means for supplying a cooling fluid to the interior of the 45 casing about the said condensation chambers therein, an exhausting chamber at the upper portion of the casing, pipes establishing communication between the upper ends of the condensation chambers and the said exhausting chamber, and an exhausting pipe 50 leading from the exhausting chamber.

In testimony whereof I affix my signature.

ERNON V. OLIVER. [L. S.]
